UNITED STATES PATENT OFFICE.

CHARLES J. BRACKEBUSH, OF NEW YORK, N. Y.

FURNITURE-CASTER.

SPECIFICATION forming part of Letters Patent No. 223,702, dated January 20, 1880.

Application filed September 25, 1879.

To all whom it may concern:

Be it known that I, CHARLES J. BRACKEBUSH, of the city, county, and State of New York, have invented certain new and useful 5 Improvements in Furniture-Casters, of which the following is a specification.

My invention relates to furniture-casters constructed with two floor-wheels hung on the same axis to a saddle which is connected with 10 the furniture through the medium of a loosely-swiveled or ball-and-socket joint, whereby the saddle is permitted to rock sufficiently to accommodate the floor-wheels to any unevenness in the floor; and it consists in the employment of a cap which is fitted below the 15 socket in the saddle, and between which and the ball the saddle plays, as will be more fully hereinafter set forth.

In the accompanying drawings, Figure 1 is 20 a side, and Fig. 2 a front, elevation of my improved caster. Fig. 3 is a vertical mid-section taken in the plane of the line xx . Fig. 4 is an inverted plan or bottom view, and Fig. 5 is a section similar to Fig. 3, showing a modification.

Let A represent the furniture-plate, which is adapted to be screwed or otherwise attached to the furniture-leg, and B the saddle, swiveled to and under the plate A, and bearing 25 two floor-wheels, C C, which are arranged on the same axis, and free to rotate independently of each other. D is an anti-friction wheel, having bearings in the saddle B, rolling against the under surface of the plate A, and 30 arranged just above and between the floor-wheels, where it will serve to transmit the weight of the furniture to the latter.

The plate A is provided with a ball-shaped or hemispherical central pendent projection, 35 E, and the saddle B is provided with a corresponding hemispherical socket, F, in its upper side, the two fitting closely together. The under side of the saddle B has a spherical swell corresponding to the socket F, and this 40 is closely embraced by a cap, G. The socket F and cap G are provided with a central hole, through which projects a stem, H, which, in Figs. 1 to 4, is a wood-screw driven from below into the furniture-leg, its head a serving 45 to hold on the cap G and sustain the saddle B.

A modification of this construction is shown in Fig. 5, where H represents a neck projecting down from and forming a part of the ball E, and screw-threaded at its end for the re-

ception of a nut, a, which is the equivalent of 55 the head a shown in Figs. 1 to 4.

The saddle B is provided with a lug or projection, b, upon its upper surface, which, normally, does not quite touch the plate A. This projection is arranged on the opposite side of 60 the ball-and-socket connection from the wheel D, and serves to prevent the too great deflection of the saddle at the front, where the wheels C C are situated, when the caster is lifted off the floor.

It will be observed that while perfect mobility is secured at the swiveled connection between the saddle and plate A, yet the parts are capable of being closely fitted to each other, so as to take up any looseness and prevent all rattling or other noise in the operation of the caster. The cap G keeps the socket F 65 always pressed closely against the ball E, and is itself kept in place by the head or nut a. When wear occurs, so that the parts become 70 loose, they can be brought together again by a turn of the screw or nut.

The entire interior of the cap G may be in contact with the socket F, as shown in Fig. 3, or it may touch the latter at its edge only, as 75 in Fig. 5, as preferred.

I am aware that it is not new to make a caster with two wheels in the same axis journaled in a saddle which is connected by a loose or open swivel to the furniture-plate, 80 and which bears an anti-friction wheel whose axis is in a continuation of a radial line extending over the space between the floor-wheels, so that the saddle may rock and accommodate the floor-wheels to the inequalities of the floor, this being shown in the English patent of Mackelcan and Murdoch, No. 8,747 of 1840. I therefore make no claim to 85 this subject-matter; but

What I do claim as my invention is as follows:

The combination of the wheels C C, saddle B, wheel D, furniture-plate A, ball E, socket F, close-fitting cap G, and stem H, with its head a, substantially as set forth.

In witness whereof I have hereunto signed my name in the presence of two subscribing witnesses.

CHARLES J. BRACKEBUSH.

Witnesses:

ARTHUR C. FRASER,
HENRY CONNETT.
